(57) **CLAIM**

The ornamental design for a face mask with adjustable ear loops, as shown and described.

DESCRIPTION

FIG. 1 is a rear perspective view of a face mask with adjustable ear loops, showing my new design with an adjustment band in a forward configuration as worn during use;

FIG. 2 is a front perspective view thereof with the adjustment bands in a rearward configuration;

FIG. 3 is a front elevational view of FIG. 2;

FIG. 4 is a rear elevational view of FIG. 2;

FIG. 5 is a right-side elevational view of FIG. 2, the left-side elevational view being a mirror image thereof;

FIG. 6 is a top plan view of FIG. 2;

FIG. 7 is a bottom plan view of FIG. 2; and,

FIG. 8 is a cross-sectional view thereof, taken in the direction of line 8-8 of FIG. 5.

The broken line showing of the person in FIG. 1 depicts environment and forms no part of the claimed design. All other broken lines in the figures represent stitching, and are part of the claimed design.
